UNITED STATES PATENT OFFICE.

JAMES A. GREENLEE, OF CHICAGO, ILLINOIS.

REINFORCED PAPER.

1,365,483.

Specification of Letters Patent. Patented Jan. 11, 1921.

Application filed August 14, 1919. Serial No. 317,393.

To all whom it may concern:

Be it known that I, JAMES A. GREENLEE, a citizen of the United States, residing at Chicago, in the county of Cook and State 5 of Illinois, have invented new and useful Improvements in Reinforced Paper, of which the following is a full, clear, and exact description.

My invention relates to a reinforced paper, and more particularly to the reinforcing of sheets of genuine vegetable parchment with cloth of any suitable or desirable weave or mesh for the purpose of utilizing the same in the wrapping of divers commodities. This invention is especially applicable for the wrapping of meats for the purpose of transportation, and is advantageous for this purpose because of the fact that the vegetable parchment is inert to and 10 unaffected by the moisture or grease from the meat, or other commodity, while the cloth upon the exterior has the advantage of forming a suitable bag or receptacle which prevents the paper from breaking or being 15 damaged.

In reinforcing paper heretofore, it has been the practice to use adhesive or cement (which is neither insoluble nor inert in the presence of moisture) to join the paper to the fabric or lining, but this is objectionable in use with edible commodities because of the use of the glue, both because of its injurious or deleterious effect upon the commodity, and because of the fact that the 20 paper becoming moist will soon dissolve the adhesive and cause the fabric lining to let go.

The tissue of paper and the fabric of cloth, because of their different structural characteristics, are capable of stretching to different extents under different conditions, moisture and temperature, and it has, therefore, become necessary, in attaining the objects herein referred to, to unite the layers 25 of tissue and fabric with a means that will not only reinforce the respective layers, but will also prevent their unequal stretching.

It is an object of my invention to provide a wrapper, the reinforcing element whereof is secured to the paper in such manner that the two elements are united and both are reinforced against unequal stretching, especially along the line of the securing means. I prefer to accomplish the foregoing and other objects by the means herein- 30 after described, and as more particularly

pointed out in the claims. Reference will now be had to the drawings forming a part thereof, in which:

Figure 1 is a plan of a fragmental portion of a sheet of my reinforced paper, the upper left hand corner whereof is broken away to disclose the fabric layer.

Fig. 2 is a transverse section of a fragmental portion of the paper, the view being greatly enlarged and exaggerated to clearly illustrate the mode of assembly.

In the drawings, similar reference characters designate the same parts in the different views, and by reference to Fig. 1, it will be observed that I employ a flat sheet of paper 5, preferably, of the type known to the trade as "genuine vegetable parchment." This vegetable parchment is made of cotton fiber that is unaffected by many acids, and has 10 the property of being insoluble in water,—in fact it can be boiled for many hours and then flattened out again without destroying its integrity. Placed against one of the surfaces of this layer of vegetable parchment is 15 a layer of fabric 6, preferably a cotton cheese-cloth, or other fabric of similar weave and mesh. These two layers, the first layer of tissue and the second layer of fabric, are joined together by means of suitable stitching 7. The stitching may be done in any manner on any suitable machine, and in any convenient design. I prefer, however, and have ascertained by experimentation, that 20 parallel rows of stitches, either longitudinal, transverse, or both, may be employed to advantage, as such row of stitching is continuous and not only joins the layers together but effectively and dependably reinforces the entire structure along the lines of 25 the stitches and prevents the unequal stretching of the respective layers, which would probably result in the rupture of either the fabric or the tissue (probably the tissue first) and thus cause a break in the 30 integrity of the assembled structure.

In the use of this reinforced paper the parchment side is, preferably, placed next the commodity and the latter is wrapped and may be sewed into a bundle, or it may be 35 found desirable to employ long strips of the reinforcing paper and wind the same, similar to bandages or spiral leggings, upon the commodity, in which event the commodity will be in better shape for handling than 40 where a package of the ordinary construction is made.

I have found that paper reinforced as above described, even after boiling for several hours, and while still wet, has sufficient strength along the lines of reinforcing stitching so that it may be easily handled and applied or removed in ordinary commercial operations, without relatively displacing or rupturing either the tissue or the fabric layers.

10 While I have shown and described certain specific means for carrying out my invention, it is to be understood that I do not necessarily restrict myself to the precise structure shown, and divers refinements and 15 changes may be made without departing from the spirit of my invention, all of which is contemplated within the scope of the appended claims.

What I claim as new is:—

20 1. An article of manufacture comprising a layer of tissue, a layer of fabric, and transverse lines of stitching through the aforesaid elements whereby said layers are united and reinforced along said lines of stitching 25 and secured against unequal stretching of the respective layers.

2. An article of manufacture comprising

a layer of tissue, a layer of fabric, and stitching through the aforesaid elements whereby said layers are united and reinforced along said stitching and secured against unequal stretching.

3. An article of manufacture comprising a layer of tissue, a layer of fabric, and continuous rows of spaced means securing said layers together whereby said elements are united and reinforced along said securing means and prevented from unequal stretching.

4. An article of manufacture comprising a layer of tissue, a layer of fabric, and means securing said layers together comprising stitching arranged in parallel rows.

5. An article of manufacture comprising a layer of tissue, a layer of fabric, and means securing said layers together comprising stitching arranged in parallel, longitudinal and transverse rows intersecting each other at substantially right angles.

Signed at Chicago, county of Cook and 50 State of Illinois, this 4th day of August 1919.

JAMES A. GREENLEE.
